DISPENSER

Harold F. Cook, Rahway, N. J., assignor to Tung-Sol Lamp Works, Inc., Newark, N. J., a corporation of Delaware

Application December 18, 1948, Serial No. 150,230

Term of patent 14 years

(Cl. D52—2)

To all whom it may concern:

Be it known that I, Harold F. Cook, a citizen of the Untied States, residing at Rahway, in the county of Union and State of New Jersey, have invented a new, original, and ornamental Design for a Dispenser, of which the following is a specification, reference being had to the accompanying drawing, forming part thereof and in which—

Fig. 1 is a perspective view of a dispenser showing my new design;

Fig. 2 is a front elevation of the dispenser shown in Fig. 1; and

Fig. 3 is a side elevation thereof.

I claim:

The ornamental design for a dispenser, substantially as shown.

HAROLD F. COOK.
